Inventor,

Peter Jeffery Mackie,
By his Atty J. H. Richards

UNITED STATES PATENT OFFICE.

PETER J. MACKIE, OF GLASGOW, SCOTLAND.

DEVICE FOR SECURING THE CORKS OR STOPPERS OF BOTTLES AGAINST UNAUTHORIZED REMOVAL.

Application filed December 7, 1921. Serial No. 520,635.

To all whom it may concern:

Be it known that I, PETER JEFFREY MACKIE, a subject of the King of Great Britain, residing in Glasgow, Scotland, have 5 invented certain new and useful Improvements in Devices for Securing the Corks or Stoppers of Bottles Against Unauthorized Removal, of which the following is a specification.

10 This invention relates to an improved device for securing the corks or stoppers of bottles against unauthorized removal and it has for its object to provide a simple and efficient device which may be readily applied 15 to existing bottles and it may be secured thereto by means of a lock and key, said device enclosing the cork so that access thereto is prevented.

20 A device according to this invention is formed in two parts hinged longitudinally together upon one edge and having upon one of its meeting edges lugs or projections 25 engaging a key operated lock mounted adjacent the other meeting edge.

25 In order that the invention may be the better understood drawings are appended in which:—

Fig. 1 is a side view of a device according 30 to this invention applied to a bottle,

Fig. 2 is a front view,

Fig. 3 is a view showing the device open,

Fig. 4 is a transverse section on line A A

Fig. 2,

35 Fig. 5 is a longitudinal section of the device upon a bottle.

Referring to the accompanying drawings *a* indicates the neck of a bottle of more or less common form and *b* the cork. *c* indicates a tubular body formed in two parts 40 connected longitudinally by means of a hinge *c*, one of said parts being a lock portion and the other being a locking portion. *d* indicates projections formed upon or secured to an extension *d* formed upon or 45 attached in any suitable manner to one of the meeting edges of the body *c* and which projections are designed to be engaged by the key operated lock, not shown, contained in a case *e* secured to the lock portion of the 50 body *c*, these projections engaging in openings *e* in the lock case *e*.

The lock portion of body *c* is provided with a disc or the like *f* adapted, when the device is in use, to cover the end of the cork,

said disc being provided with a peripheral 55 flange *f* which is disposed within the upper end of body *c*.

The lock and locking portions of body *c* are provided with internal ridges or projections *g*, *g*' adapted to engage the lower 60 edges of the projections *h*, *h*' formed upon the neck of the bottle and as the device fits snugly around said neck the said projections prevent the withdrawal of the device when locked upon the bottle.

65 In order to assist in positioning the device and limit its downward movement upon the neck of the bottle, inwardly directed projections *g* on both the lock and locking portions are provided to engage the rim of the 70 bottle said projections being conveniently formed by incising these portions of the body *c* and pressing or turning the metal inwards, the points of the projections in the case of a cork entering the exposed portion 75 of the cork. Preferably the construction of the lock is such that the projections *d* may be engaged with the bolts of the lock by simple pressure the key only being used to release the said projections.

80 Having thus described my invention, it should be understood that there may be modifications thereof and variations therein without departing from the spirit of the invention, or exceeding the scope of the appended claims.

85 What I claim and desire to protect by Letters Patent is:

1. In a device for securing corks or stoppers of bottles against unauthorized removal, a body member comprising a lock portion and a locking portion; means for connecting said portions in hinged relation; the portions being of form to surround the neck of the bottle when in operative hinged 90 relation; closure means on the lock portion for engaging the upper face of the cork or stopper; a lock case on the lock portion; the lock case being adjacent to the side of the neck of the bottle when the device is 95 in protective position; and means on the locking portion having means engageable with means appurtenant to the lock case and retainable in said engagement by key operated means contained in said case. 100

105 2. In a device for securing corks or stoppers of bottles against unauthorized removal, a body member comprising a lock

- portion and a locking portion; means for connecting said portions in hinged relation; the portions being of form to surround the neck of the bottle when in operative hinged relation; closure means on the lock portion for engaging the upper face of the cork or stopper; a lock case on the lock portion; the lock case being adjacent to the side of the neck of the bottle when the device is in 10 protective position; means on the lock and locking portions for engaging the bottle neck for preventing upward movement of the device on the neck; means on the lock and locking portions for engaging the bottle 15 neck for positioning the device on the neck and preventing downward movement of the device on the neck; and means on the locking portion engageable with means appurtenant to the lock case and retainable in 20 said engagement by key operated means contained in said case.
3. In a device for securing corks or stoppers of bottles against unauthorized removal, a body member comprising a lock 25 portion and a locking portion; means for connecting said portions in hinged relation; the portions being of form to surround the neck of the bottle when in operative hinged relation; a transverse disk on the lock portion for engaging the upper face of the cork or stopper; a lock case on the lock portion arranged longitudinally thereof; and an extension on the locking portion having means 30 for engaging means appurtenant to the lock case and retainable in said engagement by key operated means contained in said case.
4. In a device for securing corks or stoppers of bottles against unauthorized removal, a body member comprising a lock 40 portion and a locking portion; means for connecting said portions in hinged relation; the portions being of form to surround the neck of the bottle when in operative hinged relation; a transverse disk on the lock portion for engaging the upper face of the cork or stopper; a lock case on the lock portion arranged longitudinally thereof; and a longitudinal extension on the locking portion 45 having means for engaging means appurtenant to the lock case and retainable in said 50
- engagement by key operated means contained in said case.
5. In a device for securing corks or stoppers of bottles against unauthorized removal, a body member comprising a lock portion and a locking portion; means for connecting said portions in hinged relation; the portions being of form to surround the neck of the bottle when in operative hinged relation; a transverse disk on the lock portion for engaging the upper face of the cork or stopper; a lock case on the lock portion arranged longitudinally thereof and having 55 openings therein; means formed on the lock and locking portions for engaging beads on the bottle neck for preventing upward movement of the device on the neck; transverse projections on the lock and locking portions for engaging the rim of the bottle 60 neck for positioning the device on the neck and preventing downward movement of the device on the neck; and a longitudinal extension on the locking portion having means 65 engageable in said openings in the lock case and retainable in said engagement by key operated means contained in the case.
6. A device for securing corks or stoppers of bottles against unauthorized removal comprising a body formed in two parts each 70 of semi-circular cross sectional outline, a hinge connecting said parts, means upon said parts for engaging the projection adjacent the mouth of the bottle, a plate at the upper end of one part forming a closure 75 when the parts are brought together upon the bottle, projections upon one of the meeting edges disposed one adjacent the top and the other adjacent the lower end of one member of the device, a key operated 80 lock upon the other member said lock engaging said projections, securing the meeting edges together, and preventing them 85 from being sprung apart.
- In testimony whereof I have hereunto set 90 my hand and affixed my seal in the presence of two witnesses.

PETER J. MACKIE.
